UNITED STATES PATENT OFFICE.

HERBERT D. BOLTON, OF NEW YORK, N. Y., ASSIGNOR TO ELLIOTT-FISHER COMPANY, OF NEW YORK, N. Y., A CORPORATION OF DELAWARE.

RIBBON-GUIDE FOR TYPE-WRITING MACHINES.

No. 838,073.

Specification of Letters Patent.

Patented Dec. 11, 1906.

Application filed December 7, 1905. Serial No. 290,698.

To all whom it may concern:

Be it known that I, HERBERT D. BOLTON, a citizen of the United States, residing at New York, in the county of New York and State of New York, have invented a new and useful Ribbon-Guide for Type-Writing Machines, of which the following is a specification.

This invention relates to a ribbon-guide for type-writing machines of that class known as "flat-platen" or "book" type-writers.

The object of the invention is to adapt the ribbon-guide to type-heads of extraordinary width—as, for instance, those carrying words instead of letters—by providing the guide with yielding sections located at opposite sides of the type-opening in the guide to depress the active portion of the ribbon and arranged to yield when presented to one of the machine-supporting tracks or guides in order to permit the printing-point of the machine to move close thereto.

To the accomplishment of this object the preferred embodiment of the invention comprehends the construction and arrangement of parts to be hereinafter described, illustrated in the accompanying drawings, and defined in the appended claims.

In said drawings, Figure 1 is a sectional elevation of a portion of a type-writing machine equipped with a ribbon-guide constructed in accordance with my invention. Fig. 2 is a sectional plan view of a portion of the machine structure and the ribbon-guide. Fig. 3 is a plan view of the ribbon-guide inverted. Fig. 4 is a perspective view of the guide. Fig. 5 is a detail sectional view of portions of the ribbon-guide and platen, illustrating the manner in which a section of the ribbon-guide yields to enable characters to be printed close to a track or guide of the machine-supporting frame. Fig. 6 is a transverse section on the line 6-6 of Fig. 2. Fig. 7 is a similar view on the line 7-7 of Fig. 2, and Fig. 8 is a detail perspective view of one of the yielding sections of the guide.

The machine illustrated in the drawings is the Elliott-Fisher billing-machine of commerce, disclosed more fully in Patent No. 573,868, to R. J. Fisher. This machine includes in its general organization a carriage-supporting frame 1, mounted to travel longitudinally of a flat platen 2 for letter-spacing

upon tracks or guides 3, overlying the side edges of the platen and constituting the side rails of what is known as a "machine-supporting frame." Mounted to travel transversely of the platen for letter-spacing upon the carriage supporting or machine frame 1 is a carriage 4, equipped with downwardly-acting type-bars 5, one of which is indicated in Fig. 5. The type-bars are mounted to swing from a type-ring 6, suspended from the casing of the carriage 4 by hangers 7.

The ribbon mechanism includes a pair of spool-shafts 8 and 9, suitably operated and supported at opposite ends of the carriage by hangers 10. The shafts 8 and 9 support ribbon-spools 11 and 12, which rotate with the shafts to feed the ribbon 13 in one direction or the other as the carriage is advanced in the direction of letter-spacing during the printing operation. Secured within the hollow hubs 14 of the spools are bearing-thimbles 15, projecting beyond the heads of the spools to provide trunnions, which are received within the annular bearing-rings 16 of ribbon-frame-supporting brackets 17. The brackets 17 are secured in any suitable manner to the vertically-disposed end portions 18 of the ribbon supporting and guiding frame 19. The ribbon-guiding frame is designed to lead the ribbon 13 under the type-ring and extends from one spool to the other. This frame comprises end members 20 of right-angular form, having side flanges 21 and connected by a more or less open intermediate member or ribbon-plate 22.

The ribbon-plate 22 is cut out to form a comparatively wide central type-opening 23 and parallel ribbon-guides 24 and 25, paired at opposite sides of the opening 23, as best shown in Fig. 3. The ribbon 13, passing between the spools, extends around and under the ribbon-guiding frame and is threaded over the guiding-fingers 25 and under the fingers 24. The ribbon-spools and the ribbon supporting and guiding frame are designed to be shifted laterally in a manner well understood in the art, and to facilitate this movement the frame is provided with guide-studs 26, movable within guide-loops 27, secured to the type-ring 6.

The structure thus far described is not novel, but, on the contrary, is disclosed and claimed in Letters Patent No. 723,884, issued

to Laganke and Smith March 31, 1903. In the Laganke and Smith patent is furthermore disclosed the idea of bending down the inner longitudinal edges of the guiding-fingers 24 for the purpose of depressing the active portion of the ribbon—to wit, that portion which extends across the type-opening 23 and is designed to receive the impact of the type when the latter descend to the printing-point. It is with this particular feature of the construction that my present invention is primarily concerned.

It will be noted that the type-opening 23 in the ribbon-guide is quite wide. This is made necessary by reason of the fact that it is sometimes desirable to equip one or more of the type-bars with an extraordinarily-wide type-head carrying several type-faces constituting a word which in a particular line of business is used with great frequency—for instance, the word "wire" or "nails," used in the correspondence and accounts of concerns engaged in the manufacture of such goods. The provision of this wide type-opening has been accompanied by a distinct disadvantage, however, for the reason that when one of the rigid ribbon-depressing flanges of the Laganke and Smith guide is brought into contact with one of the tracks or rails of the machine-supporting frame by the movement of the carriage 4 to the right or left the travel of the carriage is arrested, although the printing-point of the machine is several letter-spaces removed from the rail. It is therefore impossible to write close to the margins of the work-sheet, and the right-hand flange constitutes a line-lock which cannot be released in order to permit the printing of one or two additional letters necessary to complete a word. To obviate this difficulty, I form the ribbon-depressing flanges separate from the ribbon-plate and mount them in such manner that when a flange contacts with one of the side rails or tracks of the machine-supporting frame said flange will yield relative to the ribbon-guide, so that the latter and the carriage may continue to move for the purpose of presenting the printing-point of the machine close to the rail in order that a word may be completed or a line of writing commenced close to the margin of the sheet. As best shown in Fig. 4 of the drawings, the ribbon-depressing flanges 28 are located at opposite sides of the type-opening 23 in the ribbon-guide and depend from the inner ends of shiftable plates or guide-sections 29. The plates 29 are supported upon the ribbon-plate 22 and are provided with longitudinal slots 30 for the reception of headed guide-screws 31, carried by the ribbon-plate 22.

To the rear ends of the plates 29 are secured springs 32, having their outer ends secured to the ribbon-guiding frame and serving to yieldingly retain the plates in their normal positions with the ribbon-depressing flanges

28 thereof held against the inner edges of the fingers 24. It will now be seen that normally the depressing-flanges 28 engage the ribbon at opposite sides of a comparatively wide type-opening in the ribbon-guiding frame to hold the active portion of the ribbon closely adjacent to the writing-surface of the platen, but that when one of these flanges is presented to one of the tracks or rails 3, as shown in Fig. 5, the movement of the carriage will not be positively arrested, but may continue the distance of one or more additional letter-spaces.

It is thought that from the foregoing the construction and operation of my improved ribbon-guide will be clearly comprehended. It is to be understood, however, that I reserve the right to effect such changes, modifications, and variations of the illustrated structure as may be necessary to effect the application of the invention to other types of machines or to other forms of ribbon-guides.

What I claim is—

1. In a type-writer, a ribbon-guide having a ribbon-engaging portion offset from the plane of the guide and yieldable lengthwise of the ribbon.
2. In a type-writer, a ribbon-guide having a relatively yielding portion yieldable independently of the ribbon and lengthwise thereof.
3. In a type-writer, a ribbon-guide having a projecting portion serving to retain the ribbon in close proximity to the platen at the printing-point and independently yieldable lengthwise of the ribbon.
4. In a type-writer, a ribbon-guide having ribbon-depressing means yieldable independently of the ribbon and lengthwise of the guide.
5. In a type-writer, a ribbon-guide having a sliding plate yieldable independently of the ribbon and having a ribbon-depressing portion.
6. In a type-writer, a ribbon-guide having a sliding plate yieldable lengthwise of the ribbon and provided with a ribbon-depressing portion, and a spring resisting the movement of the plate.
7. In a type-writer, including a platen and printing mechanism, relatively movable, and ribbon-guiding means yieldable in a direction to permit the continuation of such movement in the event of the engagement of a part of the machine by said guiding means.
8. In a type-writer, a movable carriage and ribbon-guiding means movable with the carriage in one direction and yieldable in the opposite direction.
9. In a type-writer, a movable carriage and a ribbon-guide movable with the carriage in one direction and having ribbon-depressing means yieldable in the opposite direction.
10. In a type-writer, a movable carriage, a

ribbon-guide movable therewith, a plate slideable on the guide and having a ribbon-depressing flange disposed transverse to the ribbon and extended below the plane of the 5 guide, and means opposing a yielding resistance to the movement of the plate with relation to the guide and lengthwise of the ribbon.

11. In a type-writer, a ribbon-guide having portions thereof yieldable relative to the 10 body of the guide and in opposite directions lengthwise of the ribbon.

12. In a type-writer, ribbon-guiding devices movable in different directions but in a common plane parallel with the writing-surface.

13. In a type-writer, a ribbon-guide having a type-opening, and a ribbon-depressing flange depending from the guide at one side of the opening and yieldable lengthwise of 20 the ribbon.

14. In a type-writer, a ribbon-guide having a type-opening, and ribbon-depressing flanges depending from the guide at opposite sides of the opening and yieldable in opposite 25 directions.

15. In a type-writer, a ribbon-guide having a type-opening, plates slideable on the guide at opposite sides of the opening and each having a ribbon-depressing flange depending from its inner end, and springs yieldingly retaining the plates in their normal positions.

16. In a type-writer, a carriage, a carriage-supporting structure, and ribbon-guiding 35 means arranged to be brought into engagement with the supporting structure by the movement of the carriage and yieldable to prevent obstruction of the carriage movement when so engaged.

17. In a type-writer, a platen, tracks or guides, a frame movable on the guides, a car-

riage movable on the frame, and ribbon-guiding means movable with the carriage to engage a guide and yieldable in the opposite direction to permit continued movement of the 45 carriage after such engagement.

18. In a type-writer, a platen, tracks or guides, a frame movable on the guides, a carriage movable on the frame, a ribbon-guide movable with the carriage and having a sliding plate provided with a ribbon-depressing flange movable in a path obstructed by one of the tracks or guides, and means opposing a yielding resistance to the sliding of the plate on the ribbon-guide. 50

19. In a type-writer, a platen, tracks or guides, a frame movable on the guides, a carriage mounted on the frame and movable transversely of the tracks or guides, and a ribbon-guide movable with the carriage and 60 having a type-opening and oppositely-yielding ribbon-depressing flanges depending from the guide at opposite sides of the type-opening and movable with the carriage in paths obstructed by the respective tracks or guides. 65

20. A ribbon-guide for type-writing machines, having a central type-opening, shiftable plates mounted on the guide and having ribbon-depressing flanges disposed at opposite sides of the type-opening, means for guiding the plates in their movement, and retracting-springs for the plates. 70

21. A ribbon-guide for type-writing machines, having a ribbon-depressing portion mounted to yield lengthwise of the ribbon. 75

In testimony that I claim the foregoing as my own I have hereto affixed my signature in the presence of two witnesses.

HERBERT D. BOLTON.
